United States Patent Office.

GEORGE V. SHEFFIELD, OF NORTHBIDGE, MASSACHUSETTS.

Letters Patent No. 102,720, dated May 3, 1870.

IMPROVED HEEL-STIFFENER FOR BOOTS AND SHOES.

The Schedule referred to in these Letters Patent and making part of the same.

To all whom it may concern:

Be it known that I, GEORGE V. SHEFFIELD, of Northbridge, in the county of Worcester and Commonwealth of Massachusetts, have invented certain new and useful Improvements in Counters for Boots and Shoes; and I do hereby declare that the following is a full, clear, and exact description of the same, reference being had to the accompanying drawings forming a part of this specification, in which—

Figure 1 represents a side view of one of my improved counters;

Figure 2 represents a longitudinal section of the same on line A B; and

Figure 3 represents a transverse section on line C D.

To enable those skilled in the art to which my invention belongs to make and use the same, I will proceed to describe the same more in detail.

The nature of my invention consists in an improved counter for boots and shoes, made in the peculiar manner hereafter explained.

Heretofore counters for boots and shoes have been made of several pieces of leather pasted together, or of leather, leather-board, or pasteboard, of the proper thickness, cut to the proper shape, and the edges scarfed, so as to form a thin edge. The process requires much time and labor, and also considerable skill, to fit them properly, and even then they cannot be made with any great degree of uniformity.

In the drawings—

Figure 1 represents one of my improved counters, of the form required for a boot, the ends A A being formed nearly square, so as to be stitched into the siding.

For shoes, the counters would be of a somewhat different form, but would be made in the same manner, which is as follows:

A concave die is cut in the required form of the counter, the edges of which are to be beveled off, as indicated at a a.

This die is provided with projecting pins, which enter the stock of the counter, at the points indicated at b, to hold it in place within the die during the process of manufacture.

The leather of which the counter is to be made is cut into suitable pieces, and placed upon the concave die, which is then passed under a hammer, or other suitable pressing device, by means of a movable carriage, to which it is attached, whereby the leather is forced firmly into the die, after which the die, with the counter, is passed under a rotating cutter or planing-knife, which removes all superfluous stock from the back of the counter, leaving it square with the top of the die, and thereby making the counter of the proper thickness, and also giving the proper bevel or scarfing around the edges a a.

The motion of the knife as it acts upon the counter is in the direction in which the counter is moving, which prevents the leather from crimping or doubling up during the operation, the counter being retained in position within the die by the projecting pins, which enter the side of the counter at the points indicated at b.

A counter thus made is superior to counters made in the ordinary manner, inasmuch as the fibers of the stock are forced firmly together, while, at the same time, the beveled surface is made very smooth and even.

Counters can be made by my present invention of thick upper leather, which will be equal, or nearly so, to those heretofore made of the best sole leather.

The cost of manufacture is greatly reduced, and also uniformity and cheapness are both obtained, while, at the same time, the quality of the counters produced is superior to those ordinarily made.

Having described my improvements in counters for boots and shoes,

What I claim therein as new and of my invention, and desire to secure by Letters Patent, is—

A leather counter for boots and shoes, the rounded side of which is shaped by compression in a die, and the other planed off to remove the surplus stock, as shown and set forth.

GEORGE V. SHEFFIELD.
